UNITED STATES PATENT OFFICE

BERNHARD STERNAU, OF ISLIP TERRACE, NEW YORK

DESIGN FOR A GAME BOARD

Application filed May 14, 1931. Serial No. 39,847. Term of patent 3½ years.

To all whom it may concern:

Be it known that I, BERNHARD STERNAU, a citizen of the United States, and a resident of Islip Terrace, Suffolk County, Long Island, New York, have invented a new, original, and ornamental Design for Game Boards, of which the following is a specification, reference being had to the accompanying drawings, forming part thereof.

I claim:

The ornamental design for a game board, as shown.

BERNHARD STERNAU.
